UNITED STATES PATENT OFFICE.

CONSTANTINE S. MARTINDALE, OF HARTFORD CITY, INDIANA, ASSIGNOR
OF ONE-HALF TO THEODORE CLAPPER, OF SAME PLACE.

FENCE.

SPECIFICATION forming part of Letters Patent No. 393,167, dated November 20, 1888.

Application filed August 4, 1888. Serial No. 281,985. (No model.)

To all whom it may concern:

Be it known that I, CONSTANTINE S. MARTINDALE, a citizen of the United States, residing at Hartford City, in the county of Blackford and State of Indiana, have invented new and useful Improvements in Fences, of which the following is a specification.

This invention relates to improvements in fences; and it consists in certain novel features 10 hereinafter first fully described, and then specifically claimed.

Figure 1 of the drawings represents a perspective view of a portion of a fence embodying my improvements. Fig. 2 represents 15 a vertical section on the line xx of Fig. 1. Fig. 3 represents an enlarged detail view of the end of the fence, showing how the wire is wrapped around the rails and riders. Fig. 4 is a detail view showing the construction and arrangement of the brace-stake.

Referring to the drawings by letter, A A designate the cross-stakes of the fence, the lower ends of which rest upon the ground, and B B designate the riders, which have their 25 ends b tapered, lapped, and fitted together and seated in the upper forks, a, of the cross-braces, where they are retained by the wire b', tied in figures of eight around the tops of the crossed braces. The said loops and the wires 30 forming the same are hereinafter more fully described. The riders are placed in the upper forks, a, of the crossed stakes, with their edges b' downward, so that the stakes rest against the sides of the riders.

D D designate the top or base rails of the panel, which rails have their ends d' notched or cut away to provide the flat tongues d', upon which the unreduced ends of the adjacent rails rest, thus forming a very firm and solid 40 joint between the rails. The upper edges, d', of the rails are inserted in the lower forks, a', of the cross-stakes A.

E E are the panel-rails supported by the vertical binding-braces F, adjacent to the cross-stakes, and the vertical strands of wire f, descending from and integral with the wire b'. The said strands are tied at their lower ends to the lower end of the corresponding braces, F, below the panel-rails by wire-loops f', so 50 that the panels are supported by said loops and strands.

G G are wire loops connecting the cross-stakes of each pair, and passing below the top rails, D, and H H are wire loops connecting the braces F and strands of wire f between the 55 panel-rails.

I is a longitudinally-inclined brace-stake, which has its upper end beveled on two sides, so that it will pass around in rear of the vertical brace F and rest against the adjacent 60 cross-stake. The upper end of said brace-stake is tied by the wire loop K to the cross-brace A on the opposite side of the fence, the said wire K passing under the rail D. The upper extremity of the brace-stake above the base-rails is secured to the crossed stake on the opposite side of the fence by a wire loop, L, as shown.

The top rails, D, are notched and spliced in 70 the lower forks of the crossed braces A to keep the latter extended apart, and the riders B perform the same function in the upper forks of the braces.

The braces I need not be connected with each panel, but may be situated any proper 75 distance apart—as, for instance, in every third or fourth panel.

The wires which form the figure-eight loops have their upper ends wrapped or tied to the upper ends of the braces F. Thence 80 they extend back and forth across the riders around the tops of the crossed braces, forming the figure eight around said tops, and one strand, f, is extended downward on the opposite side of the fence to the corresponding 85 brace, F, the lower end of the wire being looped or tied to said brace below the panel-rails. Thus each strip of wood F and the corresponding wire-strand, f, support the adjoining panel from the top of the pair of crossed 90 braces adjacent thereto, and the said panel is braced and stayed by the wire loops H, connecting the said strip and strand between the panel-rails, and by the wire loops G, extending between the crossed braces below the top 95 rails, D.

It will be observed that my fence is very cheap and simple and strong and durable. The rails D being spliced, as shown and described, are practically as firm and solid as 100 one continuous rail. The brace-stake resting against one of the crossed stakes and passing

around in rear of the vertical brace effect-
ually prevents any endwise movement or set-
tling of the fence as it rests against and is se-
cured to the stake, and also rests against two
5 sides of the vertical brace. In practice the
base or top rails, D, are supported at the
proper height by jacks, and notched and fitted
together, as shown. The stakes are then placed
10 over or across the splice of the rails and bound
together by the wires, which pass beneath the
rails and thereby support the same. The
jacks are then removed. The riders are next
placed in the upper forks of the crossed stakes,
15 and the long binding-wire has one end secured
to the vertical brace and passed across the
riders and around the upper ends of the stakes
and then allowed to hang past one side of the
rails. The brace is then swung downward to a
20 vertical position and the lower end of the wire
secured to the lower end of the brace, thereby
drawing the wire tightly around the upper
ends of the stakes. The panel-rails are next
placed in position and secured, their weight
25 serving to draw the long binding-wire, so that
it will still more closely bind around the stakes
and over the riders.

I am aware that it is not broadly new to
construct stake-and-rider fences, and I make
no broad claim thereto.

30 Having described my invention, I claim—

As an improvement in fences, the combina-
tion of the crossed stakes, the riders seated in
the upper forks thereof and having their ends
lapped together, the base-rails supported in
the lower forks of the stakes and having their 35
ends lapped together, the vertical brace, the
binding-wire having its upper end secured to
the upper end of the brace, and then passed
back and forth over the riders and around the
upper ends of the stakes, and thence down- 40
ward past the rails on the side opposite the
brace, and having its lower end secured to the
lower end of the brace, the panel-rails, the
loops passing between the panel-rails and se-
curing the binding-wire to the vertical brace, 45
the longitudinally-inclined brace-stake having
its upper end beveled on two sides to pass
around the vertical brace and bear against
one of the crossed stakes, and the securing-
loops L K, passed respectively above and be- 50
low the base-rails and passing around the in-
clined brace-stake and one of the crossed
stakes, substantially as shown and described.

In testimony that I claim the foregoing as my
own I have hereto affixed my signature in pres- 55
ence of two witnesses.

CONSTANTINE S. MARTINDALE.
